UNITED STATES PATENT OFFICE.

CYRILLE PATENEAUDE, OF HELENA, MONTANA TERRITORY.

MINER'S CANDLESTICK.

SPECIFICATION forming part of Letters Patent No. 289,702, dated December 4, 1883.
Application filed May 26, 1883. (No model.)

To all whom it may concern:

Be it known that I, CYRILLE PATENEAUDE, of Helena city, in the county of Lewis and Clarke, Montana, have invented a new and 5 Improved Miner's Candlestick, of which the following is a full, clear, and exact description.

This invention pertains to a miner's candlestick adapted to be conveniently carried in the 10 pocket, to be attached to perpendicular surfaces, hung upon ledges, or placed upon flat or inclined surfaces, while the candle may always be held upright.

The invention consists of the special construction and of the arrangement and combination of the parts of the candlestick, all as 15 hereinafter described and claimed.

Reference is to be had to the accompanying drawings, forming part of this specification, in 20 which similar letters of reference indicate corresponding parts in all the figures.

Figure 1 is a plan view of my new and improved miner's candlestick. Fig. 2 is a side elevation of the candlestick, showing the same 25 as it appears when placed upon an inclined support or surface; and Fig. 3 is a side elevation of the candlestick, with the hinged hook and point turned out of the handle-frame.

A represents the handle-frame of the candlestick, which frame is a spring composed of 30 the two members a a' .

To the circular head a' of the member a of the frame A is secured the pin or stud b , which passes loosely through a hole made in the head 35 a' of the member a' , and the head a' has formed in its inner face the V-shaped groove e , as shown in Fig. 1.

Upon the pin or stud b , between the heads a a' , are placed the hook B and the point C, 40 which are adapted to be turned upon b for folding the candlestick, as shown in Fig. 1, or turned out of the frame A and held by its spring action, so as to stand in the same plane or at any desired angle with the frame A, as shown 45 in Figs. 2 and 3.

Formed upon or secured to the rear end of the point C is the sleeve or socket D, for hold-

ing the candle. This sleeve is by preference made as a spring, thus adapting it to hold candles of different sizes, and upon one side of the 50 point C, or opposite sides of the pin b , and facing the V-shaped groove e , are formed the V-shaped projections e' , which are adapted to fit in the said V-shaped groove e when the candlestick is folded, and also when the point C is 55 turned out parallel with the frame A, as will be understood from Figs. 1 and 3, serving to hold the point with sufficient firmness in such positions. The projections e' also act, when C is turned to any position not in the same plane 60 with the spring-frame A, to spread the members a a' of the frame A, thus causing the frame to grasp the point C and hook B with increased force for maintaining them at any angle desired. 65

In using the candlestick, the point C is adapted to be turned out of the handle-frame A to the position shown in Fig. 3, so that it may be thrust into perpendicular surfaces in the mine for holding the candlestick with the candle in 70 socket D in vertical or upright position. The hook B is adapted for suspending the candlestick from ledges of rock or other projections in the mine. For supporting the candlestick upon a level or practically level surface, the 75 hook B and point C will be turned to stand in the same plane with the handle-frame A, which will form the base of the candlestick. For supporting the candlestick upon an inclined surface, the hook B will be turned downward 80 to bring the handle-frame A to a horizontal position and the candle held in the socket D to a vertical position, as will be understood from Fig. 2. Various other arrangements of the hook B, point C, and handle A may be 85 made, so that the candlestick may be arranged to suit almost any position where a miner may want to place the light, thus rendering the candlestick very practical and convenient in use, and when not in use it may be folded up, 90 so that it will occupy small space, and may be conveniently carried in the pocket, so as to be always at hand when needed.

The point C, besides being adapted for hold-

ing the candlestick, may be used for a scratch-awl and for various other purposes where a pointed instrument is required.

Having thus described my invention, I claim
5 as new and desire to secure by Letters Patent—

1. In a miner's candlestick, the combina-
tion, with the spring-frame A, of the sleeve
or socket D, adapted to turn upon the pin b
between the ends of the spring-frame, sub-
stantially as set forth.

2. The combination, with the spring-frame
A, of the hinged point C, formed or provided
with the sleeve or socket D, substantially as
and for the purposes set forth.

CYRILLE PATENEAUDE.
